UNITED STATES PATENT OFFICE.

CHARLES R. FARGO, OF CHICAGO, ILLINOIS, ASSIGNOR TO WILSON-JONES LOOSE LEAF COMPANY, OF CHICAGO, ILLINOIS, A CORPORATION OF ILLINOIS.

TRAY-BINDER.

1,250,293.

Specification of Letters Patent. Patented Dec. 18, 1917.

Original application filed April 20, 1916, Serial No. 92,461. Divided and this application filed April 20, 1916.
Serial No. 92,460.

To all whom it may concern:

Be it known that I, CHARLES R. FARGO, a citizen of the United States, and a resident of the city of Chicago, in the county of Cook and State of Illinois, have invented certain new and useful Improvements in Tray-Binders; and I do hereby declare that the following is a full, clear, and exact description of the same, reference being had to the accompanying drawings, and to the numerals of reference marked thereon, which form a part of this specification.

This invention constitutes a division of my co-pending application for "tray loose leaf binder", executed and filed of even date herewith.

This invention relates to an improved type of loose leaf binder of the so-called "tray" type which has come into recent use in what are known in the trade as "machine book-keeping systems." The binder is so constructed as to be used with a particular kind of stand or support to facilitate removal and insertion, as well as shifting of the pages or leaves, and in a manner such that the same are always properly aligned so that the binder may be readily closed and locked when desired to remove the same from the stand upon which it is used.

It is an object therefore of this invention to construct a tray binder comprising detachable tray cover members adapted to be locked to one another to hold the pages or leaves therebetween.

It is also an object of this invention to construct a tray binder embracing covers and back or end plates, one associated with each of the covers, to afford trays when the binder is opened and the covers separated one from another, and with said back plates provided with locking means for locking the same one to another together with said covers with pages held therebetween.

The invention (in a preferred form) is illustrated in the drawings hereinafter more fully described.

In the drawings:

Figure 1 is an end elevation of a tray binder embodying the principles of my invention.

Fig. 2 is a fragmentary detail section taken on line 2-2 of Fig. 1, with the leaves omitted from the binder.

Fig. 3 is a fragmentary view with parts

broken away and parts omitted, at the hinge end of one of the tray covers of the binder.

Fig. 4 is a top plan view of the binder in open position with the binder posts transferred to registering position.

Fig. 5 is a fragmentary detail view with parts in section, illustrating the back plates of the respective covers of the binder moved out of register with one another when unlocked.

Fig. 6 is a fragmentary plan view with parts broken away to show the construction of a portion of the covers of the binder at the points provided for the reception of the alining registration pins or binding posts.

Fig. 7 is a fragmentary detail section taken on line 7-7 of Fig. 4.

Fig. 8 is a fragmentary detail section taken on line 8-8 of Fig. 6.

As shown in the drawings:

The binder consists of covers denoted as a whole by the reference numerals 1, and at the inner ends thereof angle shaped back plates are provided, as shown in detail in Figs. 2 and 5, the angle plate of one of the covers denoted by the reference numeral 2, and that of the other cover by the reference numeral 3. The angled back plate 2, is disposed over the inner surface of the back plate 3, and means are provided for locking the same in registration with one another. For this purpose, said back plates are provided with recesses 4 and 5, respectively, at each end thereof, the recesses 4, of the plate 2, adapted to register with the recesses 5, of the plate 3, when the respective plates 2 and 3, are disposed properly one over the other.

Pivoted on the upper or inner surface of the plate 2, is a small flat crank or lever 6, with a pin 7, secured in the end thereof adapted to be engaged with the recesses 4 and 5, when the same are registered with one another. Also secured on said small crank or lever 6, is a resilient spring 8, normally sprung downwardly through a recess or slot provided in said lever 6, and provided with a detent 9, adapted to engage with an indent 10, provided to receive the same in the top surface of the plate 2, to retain said lever 6, in its inner locking position. A projecting pin 11, is also provided at each end of the back plate 3, and when

said plate 2, is moved into proper registration thereover said pins 11, fit into corner recesses 12, provided in said plate 2, to assist further in holding the plates properly registered and associated with one another. 5 The hinge connection between the respective covers 1, and the angled back plates 2 and 3, is in each instance denoted as a whole by the reference numeral 13.

10 The cover members of the binder are constructed as usual, of superposed layers of binder board or other suitable material, as shown in detail in Figs. 6 and 8, and mounted in a recessed portion of each of said cover members near the top edge thereof is a pin 15 receiving recessed block comprising sheet metal plates 14 and 15, respectively, riveted to one another and having inserted therebetween at the middle portion thereof a metal block 16. A strong and rigid retaining means to receive one of the binder impaling posts 17, inserted in the aperture therein, is thus provided, with the metal wings on each side of said block extending for a relatively 25 great distance into and between the layers of binder board to afford a strong and substantial construction.

The leaves or pages used in the binder or ledger are denoted by the reference numeral 30 18, and for the purpose of retaining the same within the ledger when the covers thereof are locked together by the respective levers 6, and pins 11, the pages are apertured to receive the binding posts 17, which 35 engage at their ends in suitable recesses provided therefor through the angled portions of the respective back plates 2 and 3.

The operation is as follows:

The binder when closed and locked is substantially similar in all respects to the usual type of loose leaf ledger, that is, the pages 40 18, are held between the covers of the binder by binding posts 17. When it is desired, however, to shift or change the pages or 45 leaves within the binder, such as when "posting the books," the binder may be conveniently taken apart by unlatching the small crank levers 6, to release the respective back plates 2 and 3, from one another, 50 to permit separation of the covers, and the detached impaling posts 17, may be inserted 55 into the recessed retaining blocks 16, provided therefor to afford a stop or registering means for the pages when laid upon the separated cover tray members. Said leaves 18, of the binder are punched along one side margin thereof so that the leaves may be turned in the ledger in a manner similar to an ordinary book and as a consequence this 60 affords a great feature of convenience over other types of loose leaf binders wherein the leaves are punched along the top or bottom margin, thereby necessitating turning the entire ledger around when referring to 65 the back surface of a sheet or leaf.

I am aware that various details of construction may be varied through a wide range without departing from the principles of this invention, and I therefore do not purpose limiting the patent granted otherwise than necessitated by the prior art. 70

I claim as my invention:

1. In a binder of the class described, cover members, angled back plates hingedly connected to each thereof adapted to be 75 registered with one another, each of said back plates provided with a notch extending from the end of the plate inwardly and the notches adapted to register, and pivotally mounted mechanism on one of said 80 plates adapted to engage said registering notches to hold said back plates and cover members locked one to another.

2. In a binder of the class described, cover members, angled back plates hingedly 85 connected to each thereof, each of said back plates provided with recesses adapted to register with one another when portions of said back plates are superposed one on the other, latching means mounted on one of 90 said back plates adapted to engage the registering recesses of said back plates to lock the same one to another, and resilient means associated with said latching means to retain the same in latched position. 95

3. A binder of the class described comprising cover members, angled back plates hingedly connected to each thereof, the back portion of one plate adapted to be disposed over the back portion of the other plate, 100 each of said back plates provided with recesses adapted to be registered with one another, latching means mounted on one of said back plates to engage the registering recesses to lock the back plates one to another, and pins rigidly secured in the other of said back plates each adapted to engage a complementary recess therefor in the complementary back plates to assist in retaining 105 said back plates locked to one another. 110

4. In a binder of the class described back plates having portions adapted to be superposed one over the other, said superposed portions having notches extending from the end inwardly adapted to register, and a 115 locking lever pivoted to one of said superposed portions at each end of the binder adapted to swing inwardly into said registered notches to lock the binder closed and to swing out from the ends of the superposed portions out of the notches. 120

5. A tray binder comprising covers, back plates hinged thereto, said back plates provided with notches adapted to register, swinging levers adapted to engage in said 125 notches to lock the plates together and friction members carried by said levers adapted to frictionally hold the levers in locking position.

6. A tray binder comprising covers, back 130

plates hinged thereto, said back plates provided with notches adapted to register, swinging levers adapted to engage in said notches to lock the plates together and friction members for holding said levers frictionally in locking engagement.

5. In a binder of the class described cover members, back members secured thereto, latching means secured to one back plate adapted to lock the back plates together, one of said back members provided with indents and resilient members secured to said latching means provided with detents to engage in said indents to hold the latching means in 15 latching position.

10. In a device of the class described cover sections, back sections hinged thereto provided with notches at their ends, a locking lever adapted to engage in the notches to 20 secure the back sections together, one of said sections provided with corner notches and pins secured to the other section adapted to engage in said notches.

15. A loose leaf binder comprising cover sections, back sections connected therewith adapted to engage one within the other, pro-

vided with notches in adjacent ends adapted to register, latching means pivoted to the inner back section at each end thereof adapted to engage in the registering notches, 30 inwardly directed pins in said outer back section and the inner section notched to engage said pins.

25. A loose leaf binder comprising covers, back members secured to the covers consisting of plates adapted one to fit over the other, said plates provided with registering notches at the ends adjacent one corner, a latching means pivoted to one plate at each end thereof to engage in said registering 40 notches, one of said plates provided with notches in the end adjacent the opposite corner from the aforesaid notches and means secured to the other plate adapted to engage in the last named notches.

35. In testimony whereof I have hereunto subscribed my name in the presence of two 45 subscribing witnesses.

CHARLES R. FARGO.
